ANDREW U. JONES, OF MONTREAL, QUEBEC, CANADA

HUMIDIFYING RADIATOR

Application filed February 15, 1932 Serial No. 593,123.

This invention relates to radiators and particularly to humidifying radiators equipped with water evaporating sections of the kind described in my co-pending application Serial No. 537,786, filed May 16, 1931.

More particularly, the present invention provides certain improvements in the design of the water evaporating sections whereby the evaporating efficiency of each section is increased in substantial degree. It also provides for a sloping arrangement of the sections which accelerates the upward flow of heated air between the sections; lends itself to effective concealment of the water courses without the use of a cabinet; and enables the width of the evaporating area of each section to be increased to a maximum degree for a given width of floor surface.

Proceeding now to a more detailed description of the invention reference will be had to the accompanying drawings wherein—

Fig. 1 is a perspective view of a humidifying radiator constructed in accordance with this invention.

Fig. 2 is a transverse sectional view along the line 2—2 of Fig. 1.

Fig. 3 is a plan view of one of the radiator sections.

Fig. 4 is a transverse sectional view along the line 4—4 of Fig. 3.

Fig. 5 is an end view of the radiator section appearing in Fig. 3.

Fig. 6 is a view, in front elevation, of the radiator section appearing in Fig. 3.

Fig. 7 is a transverse sectional view of several assembled sections of the radiator illustrating a by-pass attachment by means of which the number of sections used for evaporative purposes may be reduced.

Fig. 8 is a plan view of a modified type of radiator section, and

Fig. 9 is a transverse sectional view along the line 9—9 of Fig. 8.

The preferred embodiment of the invention is illustrated in Figs. 1 to 7 inclusive. It comprises a series of hollow radiator sections A arranged one above the other in vertical alignment, the lowermost section being supported on suitable legs 11 and the uppermost section being equipped with a removable

covering grill 12. Each section is provided at the top with an evaporating area including a long, tortuous water course of relatively narrow channel width. This water course is formed by shaping the top wall 14 of each section to provide a series of relatively narrow parallel flow channels (B, C, D, E, F, G, H and I) extending in the longitudinal direction of the section. The channels B, D, F and H slope downwardly toward one end of the section as viewed in Fig. 3 while the alternate channels C, E, G and I slope downwardly toward the opposite end of the section. The low end of each channel is in communication with the high end of the next lower channel so that a film of water traversing the water course afforded by these channels is caused to flow back and forth a number of times along the upper surface of the wall 14 before reaching the outlet 15 at the low end of the lowermost channel I.

Each section A is also provided with two series of pond-forming pockets located at opposite ends of the top wall 14. The pockets of one series are designated by reference characters 16, 17, 18 and 19 and those of the remaining series by reference characters 20, 21, 22 and 23. The water to be evaporated by each section is initially introduced into the pocket 16 and flows as a narrow film through the channel B to the pocket 20 and then back through the channel C to the pocket 17. From the pocket 17 the water flows through the channel D to the pocket 21 and back through the channel E to the pocket 18. From the pocket 18 the flow is through the channel F to the pocket 22 and back through the channel G to the pocket 19. From the pocket 19 the flow is through the channel H to the pocket 23 and then back through the channel I to the outlet 15. As the water drains through the outlet 15 it passes into a drain conduit 25 extending toward the opposite or rear side of the section. The discharge end of each conduit 25, with the exception of the conduit of the lowermost section, is positioned so that the water passing therethrough is delivered into the pocket 16 of the next lower section A, the conduit 25 of the lowermost section being connected to a drain pipe 100.

(not shown) leading to any suitable point of discharge.

The primary supply of water to the evaporating surfaces of the sections A is preferably 5 through a drip valve having its discharge positioned directly above the pocket 16 of the uppermost section A. It has not been considered necessary to show this drip valve in the present instance since the arrangement thereof will preferably be the same as described in my prior application Serial No. 10 537,786.

The coupling of the sections A to provide for the circulation of heating fluid through 15 the internal passages A' is accomplished substantially in accordance with standard practice. Each section is provided with vertical nipple receiving bosses 27 and 28 projecting upwardly from the top wall 14 in line with 20 similar bosses 29 and 30 projecting downwardly from the bottom wall 31. The angular relation between the bosses and the top and bottom walls of each section is such that, in assembled relation of the sections (see 25 Fig. 2) the body of each section is sloped so that the general plane of its top and bottom walls is inclined with respect to the horizontal.

This parallel sloping or downward inclination of the sections toward the front of 30 the radiator assembly has several important advantages. It substantially conceals from view the water course at the top of each section with the exception of the uppermost water course which is concealed beneath the covering grill 12; it provides upwardly inclined 35 air passages 33 which serve to accelerate the natural upflow of heated air between the sections A and produces a corresponding increase in the rate of evaporation; it enables 40 the sections to be provided with evaporating areas of greater width than the width of the floor space occupied by said sections and it also tends to increase the rate of evaporation 45 by accelerating the downward flow of water in the channels of the various water courses. The sections A are secured together in their assembled relation by standard connecting nipples (not shown) coupling the 50 lower bosses 29 and 30 of each section to the upper bosses 27 and 28 of the next lower section.

The foregoing embodiment of the invention has other advantages in addition to those 55 previously mentioned. The width and arrangement of the channels comprising the water course of each section provides the optimum conditions for evaporation by causing the water to flow in the form of a narrow 60 rapidly moving film which repeatedly traverses the length of the evaporating surface while advancing over the width of said surface to the drain outlet. The rapidity of flow and, consequently, the rate of evaporation 65 is also favorably influenced by the pond-

forming pockets provided at opposite ends of the flow channels. The accumulation of water in these pockets provides for the creation of a certain head pressure at the high end of each channel which naturally accelerates the downward movement of the film traversing said channel. 70

The bottom walls of the flow channels of each section may be made perfectly smooth and flat throughout their length but I prefer to provide the longitudinal corrugations indicated at 34. These corrugations serve to increase the area of evaporating surface presented by each channel without seriously impeding the flow of the film or promoting the accumulation of dirt since the valleys between the ridges of the corrugations extend in the direction of movement of the film so that any sediment deposited in these valleys is gradually moved along to the outlet. 75 80 85

When the evaporating capacity of all the sections A is not required the evaporating surfaces of one or more sections may be bypassed as indicated in Fig. 7. In this instance the water passing through the drain conduit 25 of the uppermost section A is delivered through a by-pass connection 35 to the pocket 16 of the lowermost section so that the intermediate section functions merely as a heating section. As herein shown the by-pass connection 35 is in the form of an appropriately curved tube having its receiving end detachably secured in any desired way to the discharge end of the associated conduit 25. 90 95 100

Each section A is formed to present end walls A² of rectangular outline having horizontal upper edges A³ projecting above the top wall 14 and horizontal lower edges A⁴ projecting below the bottom wall 31. The outer side wall of the channel B of each section is also formed as an upward extension of the rear body wall A⁵ and merges with the contiguous portions of the end walls A² so that its upper edge A⁶ is a continuation 110 of the edges A³. These are not essential features of design but tend to improve the general appearance of the radiator as will be apparent from inspection of Fig. 1 wherein it will be noted that the water courses are substantially concealed at the ends of the radiator by reason of the fact that the upper end edges A³ of each section closely approach the lower end edges A⁴ of the next upper section. 115 120 125

In the present instance the upwardly projecting portions of the walls A² and A⁵ are utilized, in connection with the bosses 27 and 28, the ribs A⁷ and the upwardly projecting portion A⁸ of the front wall A⁹, to provide the confining walls of the previously mentioned pond-forming pockets. The front wall portion A⁸ forms the outer side wall of the lowermost channel I and its upward pro-

jection is limited so as not to seriously obstruct the air passage 33.

In Figs. 8 and 9 I have shown a modified radiator section embodying substantially the same principles of water-course construction. In this instance the radiator section 37 is formed with a central elongated air passage 38 and a spiral water course 39. The water course has its inception at the point 40 and 10 is spiraled around the air passage 38 a number of times during its descent to the outlet 41 through which the water drains into the drain conduit 42. This construction also produces a narrow rapidly descending film 15 of water which is guided back and forth a number of times along the length of the section as it advances over the width of the section toward the outlet 41.

Having thus described my invention, what 20 I claim is:—

1. A hollow radiator section having a top water evaporating surface formed to provide a gradually descending water course having an inlet at its upper end and an outlet at 25 its lower end, and a drain conduit at the lower side of said section arranged to deliver water from said outlet to the next lower section when a plurality of said sections are arranged one above the other in vertical alignment.

2. A radiator comprising a plurality of radiator sections arranged one above the other with the body portion of the sections inclined downwardly in parallel relation to 35 provide intervening air passages inclining upwardly and rearwardly from the front of the radiator.

3. A radiator comprising a series of vertically spaced hollow radiator sections, each 40 having its top wall recessed to provide a water evaporating area and being inclined downwardly toward the front of the radiator to hide the evaporating area of the next lower section.

45 4. A hollow radiator section presenting top and bottom walls sloping downwardly toward the front of the section when the latter is supported in its operative position, the end walls of said section being of rectangular 50 outline presenting horizontal upper and lower edges projecting, respectively, above and below the said top and bottom walls.

5. A hollow radiator section presenting top and bottom walls sloping downwardly toward the front of the section when the section is supported in its operative position, the top wall of said section being recessed to 55 provide a water evaporating area and the end walls being formed to present upper horizontal edges projecting above the top wall and lower horizontal edges projecting below the bottom wall.

6. A radiator including a series of vertically spaced radiator sections, each having 60 its top and bottom walls sloping down-

wardly toward the front of the radiator, the end walls of each section projecting above the top wall and below the bottom wall and having their upper and lower edges closely approaching the opposing end wall edges of 70 adjacent sections.

7. A radiator including a series of vertically spaced radiator sections, each having its top and bottom walls sloping downwardly toward the front of the radiator, the top wall 75 of each section being recessed to provide a water evaporating area and the end walls being formed to project above the top wall and below the bottom wall so that the upper and lower edges of said end walls closely 80 approach the opposing end wall edges of adjacent sections.

8. A radiator including a series of vertically spaced radiator sections, each having its top wall formed to provide a water course 85 having an outlet through which the water normally drains into the water course of the next lower section and a by-pass conduit adapted to be connected to the outlet of a selected section to deliver the water draining 90 through the outlet to a section other than the one immediately below the said selected section.

In witness whereof I have hereunto set my hand.

ANDREW U. JONES.
